UNITED STATES PATENT OFFICE.

S. LEE TIBBALS, OF DUTCH FLAT, CALIFORNIA.

IMPROVEMENT IN DEVICES FOR CURLING HAIR.

Specification forming part of Letters Patent No. 105,519, dated July 19, 1870.

To all whom it may concern:

Be it known that I, S. LEE TIBBALS, of Dutch Flat, county of Placer, State of California, have invented an Improved Device for Curling the Hair; and I do hereby declare the following description and accompanying drawing are sufficient to enable any person skilled in the art or science to which it most nearly appertains to make and use my said invention or improvements without further invention or experiment.

My invention relates to an improved device to be used for curling the human or artificial hair, rendering the process at once easy and convenient, and doing away with the usual curl-papers or leads, as well as the heated iron, with which many persons do great injury to the hair.

In order to explain my invention so that others can make and use my device, reference is had to the accompanying drawing, forming a part of this specification, in which—

A represents a piece of plate or sheet metal, which, when it is cut or stamped out in the flat piece, is much widest at one end, tapering gradually toward the opposite end. The two opposite tapering sides of the plate A are then bent in opposite directions, so as to form an S-shaped curve, this bent plate also tapering from one end to the other.

To curl the hair it is first wet or damped in a solution or preparation which I have devised, and which is subject-matter for another patent. The hair is then wrapped spirally around the above-described tapering instrument A, and a pin, a, fixed upon the hair, so as to clasp it firmly, by inserting one of the

arms of the pin under the hair through the groove or recess b in the iron, and locking it upon the hair in this position.

The pin a consists of a piece of wire, which is bent upon itself so as to have a slight spring. One of the ends of this wire is bent or hooked so that it can be made to clasp the other, and thus hold the hair between the two prongs of the pin. The two ends of the wire may be crossed near the doubling-point, and thus give a firmer clasp. One of these pins is made to clasp the curl the entire length on each side of the iron, being inserted, as above described, under the hair through the recesses b and b', after which the iron can be withdrawn, leaving the pins to hold the curl in the proper position until it is desired to remove them.

The iron A may be formed in various ways, so as to provide a recess through which to insert the pins, and various styles and arrangements of the pins could be used to serve the same purpose; but

What I claim, and desire to secure by Letters Patent, is—

1. A hair-curling iron, when provided with grooves or recesses b b', substantially as and for the purpose described.

2. The combination, with the above-claimed curling-iron, of the locking hair-pin a, substantially as and for the purpose specified.

In witness whereof I have hereunto set my hand and seal.

S. LEE TIBBALS. [L. S.]
